UNITED STATES PATENT OFFICE.

DAVID MYERS, OF NORTH MANCHESTER, INDIANA.

AUTOMATIC BOILER-CLEANER.

SPECIFICATION forming part of Letters Patent No. 423,943, dated March 25, 1890.

Application filed October 17, 1889. Serial No. 327,323. (No model.)

To all whom it may concern:

Be it known that I, DAVID MYERS, a citizen of the United States, residing at North Manchester, in the county of Wabash and 5 State of Indiana, have invented certain new and useful Improvements in Automatic Boiler-Cleaners; and I do hereby declare that the following is a full, clear, and exact description of the same, reference being had to the annexed drawings, making a part of this specification, and to the letters of reference marked thereon.

This invention relates to certain new and useful improvements in automatic boiler-cleaning apparatus of that class in which the foul water in the upper levels of the boiler is caused to pass out from the boiler and into a precipitator, where the heavier matters are collected and left, the purified water returning to the boiler.

It has for its object to improve upon prior devices of this character, providing an improved form of skimmer, whereby better results are accomplished.

The novelty resides in the peculiar combinations and the construction, arrangement, and adaptation of parts, all as more fully hereinafter described, shown in the drawings, and then particularly pointed out in the appended claims.

The invention is clearly illustrated in the accompanying drawings, which, with the letters of reference marked thereon, form a part of this specification, and in which—

Figure 1 is a vertical section, with parts in side elevation and broken away, illustrating my improved apparatus in connection with a boiler. Fig. 2 is a side elevation of the skimmer removed and on an enlarged scale.

Referring now to the details of the drawings by letter, A designates a portion of a boiler of known construction.

C is the precipitator or cylinder, suitably supported, as shown, at some point in proximity to the boiler. It is provided with a suitable blow-off or clean-out pipe and cock *a* at the bottom, as shown in Fig. 1.

D is a tube suitably supported by the upper wall of the boiler and extending a distance within the boiler and upward a distance outside thereof, as shown in Fig. 1. Attached

to the top of the precipitator or cylinder C is a tube E. Extending downward through this tube and a distance within the cylinder is the pipe F, which at its lower end is provided with the branch pipes *b*—in this instance four in number, although the number may be varied, if desired. These branch pipes are carried by a suitable collar *c*, designed to be detachably connected with the lower end of said pipe so it may be removed for the purpose of cleaning or for other causes. This pipe passes upward through the tube and has connected therewith a horizontal pipe *d*, provided at the junction of the two with a suitable regulating valve or cock *e*. This pipe *d* communicates at its other end with the interior of the tube D, at the upper end thereof, suitable couplings being provided for the connection of these parts, as shown. 70

G is a pipe communicating with the upper end of the tube E, and extending horizontally for a short distance, thence upward to a point above the pipe *d*, thence horizontally parallel with the said pipe *d* and above the same to 75 a point over the upper end of the tube D, and then extending downward through the said tube, as shown in Fig. 1, to nearly the bottom of the boiler. A suitable regulating valve or cock *f* is provided in the said pipe G, as shown. 80

Upon the lower end of the tube D is a skimmer H, the construction of which can be best seen from Fig. 2. It consists of an inverted conical chamber, through the bottom of which the tube extends, as shown in Fig. 85 2, the lower end of the tube being provided with slots *g* and the disk or plate *h*, which is connected with the conical chamber and supported by means of the ribs or wings *i*, as shown in Fig. 2.

The operation is similar to analogous devices of this character, and a description thereof is not deemed necessary.

The branch pipes *b* are considered important, as they convey the sediment to the outer 95 and cooler parts of the precipitator or cylinder and allow only the clear water to pass up through the center of the tube E to the boiler. The peculiar construction of the skimmer is also of importance. The wings 100 serve to divide the scum, and the sloping sides of the body of the skimmer serve to guide the

foreign matters down to the apertures in the tube. The disk beneath the body serves also as a gatherer for the scum, catching what might not be gathered by the body itself.

5. What I claim as new is—

1. In a boiler-cleaner, the combination, with a precipitating-chamber, a pipe leading therefrom to the boiler, and a pipe leading therefrom to the boiler, of a skimmer within the boiler and branch pipes connected with the pipe within the precipitating-chamber, substantially as and for the purpose specified.

2. In a boiler-cleaner, the combination, with a precipitating-chamber, a pipe leading therefrom to the boiler, and a pipe leading therefrom to the boiler, of a skimmer within the boiler and branch pipes on the lower end of the pipe within the precipitating-chamber and carried by a collar detachably connected 20 with said pipe, substantially as described.

3. In a boiler-cleaner, the combination, with a precipitating-chamber, a pipe leading therefrom to the boiler, and a pipe leading therefrom to the boiler, of a skimmer within the boiler and having a conical-shaped body with 25 an apertured tube extending below the bot-

tom of said body, substantially as shown and described.

4. In a boiler-cleaner, the combination, with a precipitating-chamber, a pipe leading therefrom to the boiler, and a pipe leading therefrom to the boiler, of a skimmer within the boiler and having a conical body, a disk beneath said body, ribs connecting the disk and body, and an apertured tube extending below the bottom of the body above the disk, substantially as and for the purpose specified.

5. As an improved article of manufacture for use in boiler-cleaners, a skimmer formed with a conical body, a disk beneath the body and connected thereto by ribs or wings, and an apertured tube extending through the bottom of the body, substantially as herein shown and described.

In testimony that I claim the above I have 45 hereunto subscribed my name in the presence of two witnesses.

DAVID MYERS.
